WALDEMAR A. FALCK AND FRITZ W. FALCK, OF LOS ANGELES, CALIFORNIA, ASSIGNEES
TO LAURA G. FIXEN, OF CHICAGO, ILLINOIS.

AUTOMOBILE-SIGNAL.

1,236,830.

Specification of Letters Patent. Patented Aug. 14, 1917.

Application filed August 15, 1914, Serial No. 856,999. Renewed June 27, 1917. Serial No. 177,406.

To all whom it may concern:

Be it known that we, WALDEMAR A. FALCK and FRITZ W. FALCK, citizens of the United States, residing at Los Angeles, in the county 5 of Los Angeles, State of California, have invented new and useful Improvements in Automobile-Signals, of which the following is a specification.

This invention relates to an automobile signal or the like; and the primary object of the invention is the provision of a simple signal mechanism which will efficiently indicate the intended movements of an automobile or other vehicle. We explain our 10 invention in particular connection with vehicles; but it will be apparent that our device is not limited to this particular use, but may be used in other situations.

In its fundamentals, our device comprises 15 a casing with a source of illumination and with a pair of windows at right and left respectively, and a movable vane behind the windows illuminated from said source and adapted to be moved into position behind 20 either of the windows, the vane being preferably normally behind an intermediate solid portion of the casing wall. In the preferred form of our invention we arrange the two windows about, and extending radially from, 25 a common center; and the vane is mounted also upon this common center and has a transparent body of distinctive color, say red, through which the light from said source is transmitted through either one or 30 the other of the windows. This vane may be moved in any desired manner, by any suitable mechanism; but we prefer to use an electro-magnetic mechanism including an armature mounted upon the vane to swing 35 about a pivot and suitable electro-magnets 40 about a pivot and suitable electro-magnets for attracting the armature in either direction of movement about the pivot.

Other features and advantages of our invention are explained in the following specification; and we have shown our preferred 45 form of device in the accompanying drawings, in which:

Figure 1 is a rear elevation of our improved signal.

Fig. 2 is a view showing the same with the face of the casing removed.

Fig. 3 is a perspective showing our signal as it appears in use.

In the drawings the numeral 10 may designate a suitable casing which is preferably 55 in the form of a sector arranged about the

common pivotal center 11, and a circular portion 10^a at the bottom part of the sector portion of the casing. In the rear wall of the casing 10 we provide a pair of windows 12, which preferably have clear glasses 60 13, these windows being separated by a solid portion 14 of the casing between them. The windows 13 are preferably also in sector shape arranged radially about a common pivotal center 11, one at the right and the 65 other at the left.

Within the casing we mount a suitable source of illumination, preferably an electric light lamp 15, the lamp being located centrally behind the solid casing portion 14 70 between the two windows 12. A vane 16 is pivoted at the common pivotal center 11 and has a body portion 17 of some distinctively colored transparent or translucent material, such as red glass, or celluloid, or the like. 75 It is preferred to make the vane as light as possible so that it may be moved with a minimum expenditure of energy. At the lower part of the vane there is mounted a bar armature 18, to swing with the vane 80 about the common pivotal center 11. Immediately behind the armature we preferably arrange four electro-magnets 20 in square formation, the diagonally opposite magnets being connected in circuits by suitable wires 85 21, and each of the circuits being grounded at 22 to the casing of the device. Wires 23 lead from binding posts 24 to the respective pair of magnets, so that either pair may be energized independently of the other. Upon 90 the energization of either pair of magnets, the armature 18 is attracted to those magnets and the vane 16 is thrown to one of its two positions immediately behind the windows 12. Supply of current to either of the 95 magnet circuits may be effected in any suitable manner, the circuit being controlled by suitable switches, push buttons, or the like, in easy access to the automobile driver.

In the rear wall of the casing 10 we may 100 also cut right and left designations as shown at 30; and the transparent or translucent body 17 of the vane 16 may also pass behind these designations, so that they are shown in the color of the transparency when the 105 vane is moved to either one side or the other. At one side of the casing 10 we may provide a number holder 31 for holding the number plate 32; and a window 33 will allow light from the lamp 15 to fall upon 110 the number plate to illuminate it. We may

also have a small opening or window 35 centrally located in the rear wall of the casing 10, and this window may be provided with a red glass to serve the purpose of the usual "tail" light. When the device is in use at night, the lamp 15 is continuously illuminated; when in use in the day time, the lamp is not necessarily illuminated, 18 as day light illumination on the red body of the vane 16 will show it with sufficient clearness to make efficient indications in day light.

The vane 15 is held in its normal medial position by any suitable means, preferably by a pair of light springs 36. When the lamp 15 is in operation, the normal appearance of the indicator shows a central red light and two sector shaped white lights 20 one at each side of the central red "tail" light. When an indication is made in either of the two directions, one or the other of the white side lights becomes red; and this change from white to red is so distinctive 25 as to instantly attract attention to indicate the intended movement of the vehicle carrying the indicator. The inside of the casing 10 may be painted or otherwise coated white so as to make the lighting as efficient as 30 possible, and so as to make the two normal white lights through the windows 12 stand out as clearly as possible. The arrangement of having the two white lights showing normally and of changing one or the 35 other to red is not only very efficient because it is distinctive and attracts attention, but also because the indication of the signal may be made out to a great distance. The relative positions of the white and red may always 40 be readily seen; it is a feature of our invention that the indications are seen and recognized by recognition of the relative positions of two distinctively colored lights, rather than by the relative position of either 45 one or the other upon the automobile.

We do not limit ourselves to the specific details shown and described, reserving the right to vary those details to meet individual circumstances. In addition to the 50 features herein set forth, we wish to empha-

size the simplicity and neatness of our device, its small number of moving parts and its consequent freedom from becoming inoperative.

Having described our invention, we claim: 55

1. In an automobile signal or the like, a casing having a pair of sector shaped uncolored windows arranged radially about a common center spaced apart at right and left respectively, a source of illumination 60 in the casing, a distinctively colored transparent vane pivoted at said center immediately behind the windows and in front of said source, means to normally hold the vane in medial position between the spaced windows, and means to move the vane to position behind either window, said means including an armature mounted upon the vane and electro-magnets to attract said armature in either of two opposite directions, sub- 70 stantially as described.

In an automobile signal or the like, a casing having a pair of sector shaped uncolored windows arranged radially about a common center spaced apart at right and 75 left respectively, a source of illumination in the casing, a distinctively colored transparent vane pivoted at said center immediately behind the windows and in front of said source, means to normally hold the vane in medial position between the two spaced windows, and means to move the vane to position behind either window, said means including an armature mounted upon the vane to swing about said center, and 85 two pairs of electro-magnets arranged in square formation about said center, diagonally opposite magnets being connected together in circuit, substantially as described.

In witness that we claim the foregoing 90 we have hereunto subscribed our names this 7th day of August, 1914.

WALDEMAR A. FALCK.
FRITZ W. FALCK.
